ELECTRIC CONNECTOR

Ferman C. Doughman, Stamford, Conn., assignor
to Electrolux Corporation, New York, N. Y., a
corporation of Delaware

Application December 8, 1939, Serial No. 308,104

5 Claims. (Cl. 173—332)

My invention relates to electric connectors and more particularly to electric connectors of the readily detachable type.

An object of my invention is to provide an improved electric connector which is well protected both electrically and mechanically.

A further object of my invention is to provide an electric connector of simple construction with a minimum number of separate parts which may be readily assembled.

What I consider to be novel and my invention may be better understood by reference to the following specification and appended claims when considered in connection with the accompanying drawing, in which—

Fig. 1 is a plan view of the electric connector of my invention connected to an electric cord;

Fig. 2 is a sectional view taken along the line 2—2 of Fig. 1;

Fig. 3 is a sectional view taken along the line 3—3 of Fig. 2;

Fig. 4 is a sectional view taken along the line 4—4 of Fig. 3;

Fig. 5 is a sectional view taken along the line 5—5 of Fig. 4; and

Fig. 6 is an exploded view in perspective of the parts of the connector and an electric cord.

Referring to the drawing, 10 indicates a shell of soft rubber, or other flexible non-metallic material. Shell 10 has a cord receiving passage 11 communicating with a central chamber 12. Two terminal contacts 13 are located in the chamber 12 and connected to electric conductors 14 by means of terminal binding screws 15. Terminal contacts 13 are held in spaced relationship by a spacer 16 formed of a non-metallic material such as hard rubber or a phenolic condensation product. Terminal contacts 13 are provided with coverings 17 of insulating material having flanges 18 received in recesses 19 in spacer 16. Flanges 18 are also seated in recesses 20 provided in the inside walls of shell 10. The flanges 18 serve to lock the spacer 16 and terminal contacts 13 in the shell 10.

Coverings 17, as best indicated in Fig. 3, extend beyond the ends of contacts 13. This protects the adjacent portions of shell 10 from any arc which may be drawn upon the separation of contacts 13 from any contacts to which they may be connected. If the shell 10 were made of rubber any arc striking it would have a deleterious effect.

Spacer 16 is provided with an enlarged end 21 having grooves 22 in which the conductors 14 are positioned. The conductors 14 are pressed

by enlarged end 21 against the walls of shell 10 thereby relieving the conductors 14 from any strain at their points of connection to the terminal contacts 13. Any strain resulting from a pull on the cord to disconnect the connector is transmitted by the conductors 14 at the points they engage the shell 10 directly to the shell.

The connector is assembled by first inserting the electric conductors 14 through the passage

10 11 of the shell 10 and sliding the shell 10 back away from the ends of the conductors 14. The

terminal contacts 13 are then connected to the ends of the conductors 14. The terminal contacts 13 and the spacer 16 are locked in their

15 relative positions with the flanges 18 seated in recesses 19 by pins engaging the terminal contacts 13. The assembly of the connector in this

stage is illustrated in Fig. 6. The conductors 14 are then held as the shell 10 is pulled over

20 the terminal contacts 13 and spacer 16. The shell 10 expands to permit the spacer 16 and

contacts 13 with the outwardly extending flanges 18 to enter the chamber 12. When the contacts 13 and spacer 16 have reached their proper position

15 in the chamber 12 of shell 10, the flanges 18 enter the recesses 20 provided in the inside walls of shell 10. The assembly of terminal contacts 13 and spacer 16 is then securely held in

position within the shell 10.

30 What I claim is:

1. An electric connector including a soft rubber shell, a pair of terminal contacts, a covering of non-metallic material for each of said contacts having an outwardly extending shoulder,

35 electric conductors connected to said terminals, a spacer located between said terminals having recesses to receive the shoulders of the coverings of said terminals, and strain relief means for

40 said conductors formed integrally with said spacer, said shell having recesses to receive the shoulders of the coverings of said terminals, whereby said terminals and said spacer are

locked in position in said shell.

45 2. An electric connector including a soft rubber shell, a pair of terminal contacts, a covering of non-metallic material for each of said contacts extending beyond one end of the contacts and having an outwardly extending shoulder,

50 said shell having a recess to receive the shoulder of said contacts, electric conductors connected to said terminals, a spacer located between said terminals having recesses to receive the shoulders of the coverings of said terminals,

55 and strain relief means connected to said spacer

for holding said conductors in engagement with said shell.

3. An electric connector including a soft rubber shell, a pair of terminal contacts open at one end; a covering of non-metallic material for each of said contacts extending beyond the open ends and having an outwardly extending shoulder, binding screws in engagement with said terminals, electric conductors connected to said terminals by said binding screws, a spacer located between said terminals having recesses to receive the shoulders of the coverings of said terminals, and strain relief means for said conductors connected to said spacer for holding said conductors in engagement with said shell, said shell having recesses to receive the shoulders of said terminals, whereby said terminals and said spacer are locked in position in said shell.

4. An electric connector including a shell of resilient material having a chamber open at one end and communicating with a cord receiving passage in the other end, a pair of terminal contacts located in the chamber of said shell, an outwardly extending shoulder formed on each of said contacts, said shell having recesses to

receive said shoulders, and a spacer of non-metallic material for said contacts located in the chamber of said shell and having recesses to receive said shoulders, said shoulder of each contact engaging both said shell and said spacer whereby the connector is held in assembled relation by engagement of the shoulders of said contact with said shell and said spacer.

5. An electric connector including a shell of resilient material having a chamber open at one end and communicating with a conductor receiving passage in the other end, a pair of terminal contacts located in the chamber of said shell and having outwardly extending shoulders, said shell having recesses to receive said shoulders, a spacer of non-metallic material for said contacts located in the chamber of said shell and having recesses to receive said shoulders, and a strain relief member connected to said spacer for holding said conductor in engagement with said shell whereby the connector is held in assembled relation by engagement of the shoulders on said contacts with said shell and said spacer.

FERMAN C. DOUGHMAN.
